Primary Examiner — Eric L Goodman*Assistant Examiner* — Vanessa Martinez(74) *Attorney, Agent, or Firm* — Theodore S. Lee, Esq.(57) **CLAIM**

The ornamental design for a vehicle headlight, as shown and described.

DESCRIPTION

FIG. 1 is a perspective view of a vehicle headlight;

FIG. 2 is a right side view thereof;

FIG. 3 is a front view thereof;

FIG. 4 is a left side view thereof;

FIG. 5 is a back view thereof;

FIG. 6 is a top view thereof; and,

FIG. 7 is another perspective view thereof.

My design includes a mirror image of the embodiment depicted. In the drawings, the dash line included denotes environment and is not part of the claimed design.
